UNITED STATES PATENT OFFICE

2,594,774

TOOL FOR REPAIRING SLIDE FASTENERS

John S. Harris, Orlando, Fla.

Application December 31, 1948, Serial No. 68,580

3 Claims. (Cl. 81—5.1)

1

This invention relates to improvement in tools, and especially tools for the repair of "zipper" members.

To those familiar with the zipper art it is common knowledge that the "zipper" teeth become bent and out of line rendering actuating of the "zipper" slider impossible; further, the slider may become damaged, out of line, or corroded, or the locking means on the "zipper" tab out of alignment or bruised thereby not locking the slider against a lace, therefore, primary object of this invention is to provide a tool whereby "zipper" repair may be made by correction or replacement of damaged members instead of following the common practice of replacing a complete "zipper."

This invention resides substantially in the combination, construction, arrangement and relative location of parts, all in accordance with the disclosure herein.

In the accompanying drawings:

Figure 1 is a plan of the improved tool.

Figure 2 is a side view thereof when the tool is in normal inactive position:

Figures 3 and 4 are opposite end views thereof.

Figure 5 a section on line 5—5, Figure 2.

Figure 6 is a fragmentary view of a portion of one of the jaws as viewed on the line 6—6, Figure 2.

Figure 7 is a view similar to Figure 2, illustrating stop means provided by closing of forward jaws, whereby, rear and lateral jaws, when in closed position, retain a slight spacing to prevent bruising of member being repaired thereby.

Figure 8 is a view of the lateral jaws broken away and viewed from their outer end.

The true nature and manner of use of a device in accordance with this invention will be best understood by a detailed description of the form thereof, shown in the drawings in an illustrative sense.

Now referring to the drawings which illustrate my preferred form of structure it will be observed that this invention includes a pair of handle members 2 and 3 of such size and shape as to be conveniently grasped in the hand of an operator, and connected by a single pivot 4.

Reference to the drawings further teaches that said handles 2 and 3 carry four sets of jaw members, indicated as 5 and 6, 7 and 8, 9 and 10, 11 and 12, respectively.

Jaw member 6 is formed with a central teat 14 extended outward on its outer end face and is opposed thereto in outer edge face of jaw 5 by a concaved recess 15. By providing the opposed

2

recess it is possible to straddle the "zipper" hinge between "zipper" tab and slider thereby removing danger of bruising same when clamping pressure is placed upon the "zipper" locking cam by the teat 14 thru means of jaw member 6.

Jaw members 7 and 8 provide means for "zipper" tooth and "zipper" tab replacement, prong 20, Figure 8, being wedged, on closing of the jaws 7 and 8, between the "zipper" tooth and tape thereby prying said tooth free of the "zipper" tape for removal therefrom and substitution of an operable tooth. In replacing a "zipper" tooth same is inserted in one of the slots 21, which are of varied depth, on either jaw, depending on size of tooth, the fastening prongs which secure the tooth to the tape being open, "zipper" tooth is then set to the "zipper" tape and clamped thereto, purpose of the opposed slots being to retain the "zipper" tooth straight to the "zipper" tape while being engaged therewith. For "zipper" tab replacement the "zipper" tab hinging prongs are set in hinge socket of the slider and clamped into position by inserting tab between slots 23 and 24 then manually holding the slider so that the hinge socket is between tab hinging prongs, then clamping the prongs into the socket, however in this operation care must be exercised not to crush either the "zipper" prongs or "zipper" socket which would destroy pivotal relation therebetween, therefore observation of Figure 7 will teach that complete closing of jaw members 7 and 8 is prevented, a space corresponding to the width of the socket being maintained by stop means provided by jaw members 5 and 6 which are timed by reason of their structure and pivotal relation of members 2 and 3 to completely close simultaneously with the jaw members 7 and 8 reaching the defined space relationship.

When "zipper" slider fails to lace, requiring removal by jaw members 11 and 12 for repair or replacement, the "zipper" must be laced for replacement of "zipper" slider, therefore, I provide jaw members 9 and 10, the opposed faces having central recesses, 26 and 27, respectively, running lengthwise of the jaws with inner end curved outward, Figure 5, which, when jaws are applied to the "zipper" and slid thereover, act as a "zipper" slider, the curved ends being means to urge the opposed "zipper" teeth together, care must be exercised not to bruise or crush the teeth, therefore, spacing corresponding to the elevation of the "zipper" teeth is provided for in a like manner and simultaneous with the spacing of jaw members 7 and 8 by the stops or jaw members 5 and 6.

Jaw members 11 and 12 comprise the pin shaped jaw member 11 having a head 13, said member being in central transverse relation to and slidably traversing nose portion 30, for action to and from jaw member 12, extended to inner face of nose member 31, actuated by said member to and from jaw member 12, during use of the tool, and circumscribed by a coil spring 32 between the opposed nose portions, said spring forming means to return and hold the tool in inactive position, Figure 2, and opposed by jaw member 12 of wedge shaped bill structure with the bill point in vertical alignment with center of pin head 13, and normally spaced thereabove sufficient to insert a "zipper" slider, end to end, therebetween, with the closed end resting on pin head 13 and its open end in position to receive the wedging bill to spread the "zipper" slider for removal from a jammed position, for resetting of slider or for removal of "zipper" slider for replacement.

From the above description it will be apparent to those skilled in the art that the details of construction illustrated herein may readily be varied without departure from the novel subject matter herein disclosed. I do not, therefore, desire to be strictly limited by the disclosure but rather by the claims granted me.

What is claimed:

1. A tool of the kind described, comprising a pair of crossed pivotally connected operating levers arranged for alignment with each other in their crossed relation, opposed portions of one end of the levers extending laterally thereof and forming stops, a wedge shaped bill element carried by one of the levers, and projected laterally at substantially right angles thereto from an outer face of the same, and a displaceable member carried by the other lever and having an anvil head opposed to and coacting with the bill element on operating the levers.

2. A tool of the kind described, comprising a pair of crossed pivotally connected operating levers arranged for alignment with each other in their crossed relation, opposed portions at one end of the levers extending laterally thereof and

5 forming stops forming continuations of the levers, a wedge shaped bill element carried by one of the levers, and projected laterally at substantially right angles thereto from an outer face of the same, a displaceable member carried by the other lever and having an anvil head opposed to and coacting with the bill element on operating the levers, and resilient means circumscribing the member and abutting both levers to maintain the bill element and member in normal inoperative position.

10 3. A tool of the kind described, comprising a pair of crossed pivotally connected operating levers arranged for alignment with each other in their crossed relation, opposed portions at one end of the levers extending laterally thereof and forming stops, a wedge-shaped bill carried by and projecting laterally and at substantially a right angle to the outer face of one lever, and a displaceable member carried by the other lever and extending laterally in the same general direction as said wedge-shaped bill, said displaceable member having an anvil head thereon opposed to and coacting with said bill upon operating said 15 levers.

20 25 JOHN S. HARRIS.
